UNITED STATES PATENT OFFICE.

JAMES BUTLER, OF PHILADELPHIA, PENNSYLVANIA.

PAPER-WINDER.

No. 830,296.

Specification of Letters Patent.

Patented Sept. 4, 1906.

Application filed May 31, 1906. Serial No. 319,565.

To all whom it may concern:

Be it known that I, JAMES BUTLER, a citizen of the United States, residing in Philadelphia, Pennsylvania, have invented certain Improvements in Paper-Winders, of which the following is a specification.

My invention relates to certain improvements in winders used in connection with machines for supercalendering paper.

10 The object of my invention is to so construct a paper-winding machine that the roll of paper need not be taken off the machine and turned, as is customary in machines used in connection with supercalendering-ma-
15 chines.

15 In the accompanying drawings, Figure 1 is a view of my improved paper-winding machine; and Fig. 2 is a sectional view on the line 2 2, Fig. 1, showing my improved wind-
20 ing-machine in connection with a series of supercalendering-rolls, the rolls being shown in diagram and the frame in dotted lines.

25 Supercalendering-rolls are for the purpose of recalendering paper, so as to produce a smooth surface on the paper. The paper is passed through the set of calendering-rolls A, the rolls *a a a a* of which are metal-faced rolls, and the rolls *b b b* are paper or cotton faced. In the present instance the paper *x*
30 passes over the roll *a* and between the rolls *a b*, as indicated in Fig. 2, partly around a roll *b*, then between it and another roll *a*, and so on through the machine, and if it is desired to pass the paper through the rolls a second
35 time the roll of paper must be so placed that the same surface will be acted upon by the metal rolls as was previously acted upon.

40 Ordinary paper-winding machines are so constructed that in order to have the paper pass off the roll in the right direction the filled roll must be removed from the machine and turned end for end and again placed in position, so that the face of the paper to be acted upon will be in proper position. By my in-
45 vention I avoid the necessity of removing the roll from the machine by providing means for turning the roll and the frame carried by it end for end. This I accomplish in the fol-
50 lowing manner: B B are the side frames of the winding-machine, on which is mounted a shaft C, having trunnions *c c*, mounted in bearings on said frames B. This shaft C has a gear-wheel *c'* at one end which meshes with a pinion *c''* on the shaft *c''*, mounted in a bear-

ing on one of the frames B. On the opposite 55 end of the shaft is a worm-wheel *c⁴*, which meshes with a worm *c⁵* on a shaft *c⁸*, which has a hand-wheel *c⁹*. When it is wished to turn the shaft C to reverse the position of the spindles D D', upon which the paper is 60 wound, the pin *c⁶*, which is connected to the lever *c⁷*, is withdrawn from a hole in the gear-wheel *c'*, the worm-shaft is turned slowly, turning the shaft C and reversing the position of the two spindles D D'. 65

The spindle D is mounted on a frame E, carried by the shaft C, and the spindle D' is mounted on a frame E', also carried by said shaft C. On the shaft are projecting hubs *e e*, Fig. 2, on which the frames E E' are piv- 70 oted, the frames being held in position by plates *e'* and screws *e''*. I preferably provide antifriction-rollers *e³* between the bearing-surfaces of the two frames E E' and the enlarged portion C' of the shaft C, so that the 75 frames can be readily turned end for end.

Projecting from each side of the shaft C are bearings *f f*, in which are mounted bolts *f'*, provided with handles *f²*. These bolts are arranged to be projected into holes in the 80 ends of the frames E E', so as to lock the frames when they are turned into position.

The ends *d d'* of the two shafts D D' are shaped so that they can be coupled to a driving-shaft and a tension-shaft. The ends are 85 squared in the present instance to fit the couplings.

On the frame B is a bracket B', on which are mounted two shafts G and H. The shaft G is mounted in bearings at the upper end of the 90 bracket, and the shaft H is mounted in bearings at the lower end of the bracket. Adapted to slide on the shaft G is a coupling *g*, having a socket corresponding in shape to the end of the spindles D D'. This coupling can 95 be shifted by means of a lever *g'*.

On the shaft G is a friction-drum *g²*, and adapted to engage the drum is a friction-band *g³*. The pressure of this band can be regulated so that more or less tension can be 100 applied to the spindle D and the roll of paper thereon. By this means the roll will not unwind faster than the calendering-rolls can take up, and the paper will always be under tension.

105 The shaft H is a driving-shaft, having a double-flanged belt-pulley *h* in the present instance. This shaft H also has a driving-

coupling h' , the socket in which is shaped to fit the ends of the spindles D D'. The coupling is shifted by a lever h^2

1 is a carrier for a tension-roll which bears 5 upon the driving-belt, so as to place more or less pressure upon the belt. The tension-roller is regulated by a shaft i , having a hand-wheel i' . This mechanism forms no part of my invention, as it is commonly used in 10 winding-machines.

The shafts D D' are mounted in their frames E E', so that they can be readily removed. The boxes n are made in two parts, one part being removable and connected to a 15 clamp-lever n' , so that on moving the lever in one direction the box is closed and on moving in the other direction the box is opened.

The operation of the machine is as follows: The roll of paper as it comes from the machine 20 is placed on a spindle D, for instance, in such position that the paper will unwind from the top of the roll, as indicated in Fig. 2. The paper x then passes between the rolls of the calenders A in the manner shown in said figure, with the one surface of the paper in contact 25 with the metal-faced rollers, and the paper returns to the winding-machine and is wound on the spindle D' from the bottom, as indicated. As is required in supercalendering, 30 the paper is passed through the calendering-rolls several times, according to the character of surface required, and if the carrier-shafts C were simply turned so as to bring the roll of paper on the spindle D' in the position 35 of the roll of paper on the spindle D the paper would lead off the roll from the bottom instead of the top, which is objectionable, as it would bring the surface to be calendered in contact with the paper-surface of the calendering-rolls instead of the metal surface. By 40 turning the roll of paper end for end the paper is brought into proper position to lead off, so that the previously-calendered surface will again come in contact with the metal rolls. 45 This is accomplished by simply withdrawing the coupling h' and the bolt f' , which locks the frame E', carrying the spindle D', then the frame and its spindle is turned end for end on the pivot e , the bolt is thrown forward 50 to engage the frame and lock it in position, then the coupling g on the shaft G is withdrawn from the spindle D, and the worm c^5 , wheels $c^3 c^2 c'$ are set in motion, so as to turn the shaft C and bring the spindle D' in the 55 upper position and the spindle D in the lower position. The paper is then wound from the spindle D', passing between the calendering-rolls and wound upon the spindle D, when the above operation is repeated. Thus the spindles D D' are not removed from the machine, 60 except when the calendering is completed, and considerable delay and the necessity of lifting the heavy load are avoided.

It will be understood that while I have 65 shown power gearing-by which the driving-

shaft can be turned it may be turned by hand without departing from my invention and power can be applied to the worm-shaft, if desired.

I claim—

1. The combination in a paper-winding machine, of a shaft, a carrying-frame thereon for the paper, said frame being so pivoted that it can be turned end for end, substantially as described.

2. The combination in a paper-winding machine, of a shaft, two carrying-frames pivoted thereto, a spindle mounted on each frame, the said frames being so pivoted to the shaft that they can be turned end for end, substantially as described.

3. The combination in a paper-winding machine, of a shaft, two carrying-frames pivoted to the shaft so that they can be turned end for end, a spindle on each frame, a power-driven shaft, and a coupling arranged to couple the power-driven shaft to either end of one of the spindles, substantially as described.

4. The combination in a paper-winding machine, of a shaft, two carrying-frames pivoted to the shaft so that they can be turned end for end, a spindle on each frame, a driving-shaft, and a coupling on the shaft, each end of both spindles being shaped so as to be engaged by the coupling substantially as described.

5. The combination of the frame of a paper-winding machine, a longitudinal shaft mounted in said frame and having projecting pivot portions, a carrying-frame mounted on each pivot portion, a spindle on each frame, means for coupling one of the said spindles to a driving-shaft, and means for locking both carrying-frames in position, substantially as described.

6. The combination of a longitudinal shaft, two carrying-frames pivoted thereon, a spindle on each frame, means for coupling one of the spindles to driving mechanism and the other spindle to friction mechanism, and means for turning the shaft so as to reverse the positions of the spindles, the frames being arranged so that the spindles can be turned end for end, substantially as described.

7. The combination of the frame of a paper-winding machine, a longitudinal shaft, two carrying-frames pivoted to the said shaft, a spindle on each frame, a power-driven shaft mounted on the frame of the machine, means for coupling the said shaft to one of the spindles, a shaft also mounted on the frame of the machine, a friction-drum carried by said shaft, and means for coupling the friction-shaft, to the other spindle substantially as described.

8. The combination in a frame of a paper-winding machine, of a longitudinal shaft, means for turning said shaft to a given position, means for locking the shaft in position,

two carrying-frames pivoted to the shaft so that they can be turned end for end, means for locking the frame to the shaft, a spindle detachably mounted on each frame, each 5 spindle having a squared end, a power-driven shaft carried by one of the frames of the machine, a coupling mounted on the said shaft arranged to be shifted to engage the squared end of one of the spindles, a friction-shaft at 10 the upper end of the machine, a friction-drum thereon, and a coupling-sleeve mount-

ed on the said friction-shaft and arranged to slip over the squared end of the other spindle, substantially as described.

In testimony whereof I have signed my 15 name to this specification in the presence of two subscribing witnesses.

JAMES BUTLER.
